CLAIM

The ornamental design for a product display pallet, as shown and described.

DESCRIPTION

FIG. 3 is a right side elevational view of the product display pallet shown in FIG. 1, the left side elevational view being a mirror image thereof;

FIG. 4 is rear elevational view of the product display pallet shown in FIG. 1; and,

FIG. 5 is a top plan view of the product display pallet shown in FIG. 1, the bottom plan view being plain and non-ornamental.

FIG. 1FIG. 2

FIG. 3

FIG. 4

FIG. 5

UNITED STATES PATENT AND TRADEMARK OFFICE
CERTIFICATE OF CORRECTION

PATENT NO. : Des. 352,619
DATED : November 22, 1994
INVENTOR(S) : Pigott et al

It is certified that error appears in the above-identified patent and that said Letters Patent is hereby corrected as shown below:

On the title page, insert the following:
